Primary Examiner — Dana L Meyrow(74) *Attorney, Agent, or Firm* — Fross Zelnick Lehrman & Zissu, P.C.; Charles T. J. Weigell, Esq.(57) **CLAIM**

The ornamental design for a bottle, as shown and described.

DESCRIPTION

FIG. 1 is a front view of a bottle showing my new design (with the rear view being the same);

FIG. 2 is a side view of the bottle shown in FIG. 1 (with the other side view being a mirror image thereof);

FIG. 3 is a top view of the bottle shown in FIG. 1;

FIG. 4 is a bottom view of the bottle shown in FIG. 1; and, FIG. 5 is a front perspective view of the bottle shown in FIG. 1.

The broken line depicting the bottle top and portion of the bottle sole shows unclaimed subject matter.
